OR D 12,604

DESIGN FOR A STOVE.

Design No. 12,604, dated December 20, 1881.

UNITED STATES PATENT OFFICE.

H. CLAY BASCOM AND CYRUS A. HODGES, OF TROY, N. Y., ASSIGNEES TO N. S. VEDDER PATTERN WORKS, BASCOM, GALBRAITH & CO., OF SAME PLACE.

DESIGN FOR A STOVE.

SPECIFICATION forming part of Design No. 12,604, dated December 20, 1881.

Application filed November 18, 1881. Term of patent 7 years.

To all whom it may concern:

Be it known that we, H. CLAY BASCOM and CYRUS A. HODGES, each a citizen of the United States, residing in the city of Troy, in the county of Rensselaer and State of New York, have jointly invented and produced a new and original Design for Cooking Stoves and Ranges, of which the following is a specification, reference being had to the accompanying cut, print, or engraving of a cooking stove or range having said new design.

The design for the ornamental shelf-crest A consists of the lower band part, *a*, having the ornaments *a'*, in combination with the upper open-work portion, *b*, consisting of the combined fillets, scrolls, and ornaments, all shaped and arranged together as represented in the aforesaid print.

The design for the shelf-support B consists of the middle pipe portion, *C*, having thereon the lower compound panel ornament, *c*, and upper panel ornament, *d*, in combination with the double reversed wing-brackets *D D*, having the lower panels, *e e*, with the plant ornaments *e' e'* therein, and the upper panels, *f*, with the ornaments *f'*, the whole being shaped and arranged as represented in the accompanying engraving.

The outline form of the shelf-support B is essentially the same as that shown in United States Design Patent No. 12,092, January 4, 1881; but the ornamentation thereof above described, and shown in the aforesaid engraving, is very different.

The design for each of the doors or plates E F G consists of the quadrilateral panel *g*, having thereon the compound lower corner ornament, *h*, the diagonally-opposite upper corner ornament, *i*, and the intervening representation of a flowering plant, *j*, all composed, shaped, and arranged substantially as shown in the aforesaid cut.

The design for the panel ornament H consists of the two convexly-curved side edges, *k*, two convexly-curved end edges, *l*, four intermediate angular edge parts, *m*, name-plate *n*, extending obliquely across the body portion, and having angular ends conformed to two of the diagonally-opposite angular parts of the body, and the raised fillets *o* along the edges of said name-plate and body portion, and enclosing the two vine-like scroll-form ornaments *p*, all shaped and arranged in combina-

tion substantially as shown in the aforesaid print.

The design for the panel border for the oven-door I consists of the outer convex molding, *q*, lower corner compound ornament, *r*, having the side florets, *r'*, the diagonally-opposite compound corner ornament, *s*, and the two other diagonally-opposite corner ornaments, *t t'*, all composed, shaped, and arranged together substantially as shown in the aforesaid engraving.

The design for the oven-door consists, essentially, of the compound central ornament, *H*, in combination with the corner ornaments, *r s t*, all shaped and arranged so as to present substantially the appearance represented in the accompanying cut.

The design for the closet-door J consists of the compound central panel ornament, *u*, in combination with the end panel ornaments, *v w x*, all composed, shaped, and arranged substantially as shown in the aforesaid print.

What we claim as our joint invention is—

1. The design for the shelf-crest A, consisting of the lower band, *a a'*, in combination with the open-work upper portion, *b*, composed, shaped, and arranged as shown and described.

2. The design for the shelf-support, consisting of the middle part, *C d*, and the two side parts, *D e e' f f'*, all shaped and arranged as set forth.

3. The design for the small doors or plates E F G, consisting of the parts *g h i j*, all shaped and arranged as set forth.

4. The design for the panel ornament H, composed of the parts *k l m n o*, and *p*, all shaped and arranged as set forth.

5. The design for the panel border of the oven-door, consisting of the parts *q r r' s t t'*, all shaped and arranged as set forth.

6. The design for the oven-door, consisting of the parts *H r s t*, composed, shaped, and arranged as set forth.

7. The design for the closet-door, composed of the ornaments *u v w x*, shaped and arranged as set forth.

In testimony whereof we hereunto set our hands, in the presence of two subscribing witnesses, this 16th day of November, 1881.

H. CLAY BASCOM.
CYRUS A. HODGES.

Witnesses:

AUSTIN F. PARK,
JAMES T. GOODFELLOW.
